ABSTRACT

Manual reinstitution of production of an attenuated strand, by a drafting system of a textile yarn spinning machine which cooperates with a device for interrupting feeding of roving strands, is facilitated by the provision of slotted guides or trumpets constructed for receiving a roving strand by lateral movement of an intermediate portion of a running length of the strand relative to the guide.

PATENTED SEP 3 1974

3,832,839

TEXTILE YARN SPINNING MACHINE WITH
ROVING INTERRUPTION APPARATUS AND
SLOTTED GUIDES

It has heretofore been the practice, in the production of textile yarn from textile fibers through the use of textile yarn spinning machines, to accommodate the interruption of yarn formation by breakage of an attenuated strand issuing from a drafting system by taking-up the attenuated strand issuing from the drafting system, using equipment known as "vacuum end collection" systems. In such practices, reinstitution of yarn production (in the process known as "piecing-up") has involved the joining of a strand of yarn to the attenuated strand issuing from the drafting system, either by a manual operation performed by an operator or by a mechanical operation performed by an appropriate apparatus. Suitable apparatus have been disclosed in a number of prior patents, to which the interested reader is referred, including by way of example only U.S. Pat. No. RE. 26,360 to Escursell-Pratt; U.S. Pat. No. 3,373,551 to Gillono et al.; U.S. Pat. No. 3,403,866 to Bell et al. and U.S. Pat. No. 3,486,319 to Lee et al.

More recently, it has been proposed that the roving strands normally received by drafting systems of the textile yarn forming machine, to be drawn and delivered as attenuated strands, be interrupted in the absence of continuing production of yarn. Through interrupting delivery of the roving strands, certain difficulties and deficiencies possibly encountered are avoided. A more complete understanding of the desirable results thus achieved and of a successful operating embodiment of such apparatus may be gained from U.S. Pat. No. 3,726,072 to Ford et al. Other examples of roving strand feeding interruption devices may be found in the disclosures of U.S. Pat. No. 3,403,866 to Bell et al.; U.S. Pat. No. 3,498,039 to Kent et al. and U.S. Pat. No. 3,568,425 to Zegna et al.

While various solutions proposed by the prior patented apparatus and methods, briefly referred to hereinabove, have in certain instances been successfully adopted, the interruption of roving strand feeding to a drafting system has been found to raise certain difficulties and deficiencies. In practice, the reinstitution of the production of yarn by a particular drafting system along a textile yarn spinning machine must be accomplished manually at least in part after roving strand feeding has been interrupted. More specifically, where no attenuated strand is issuing from the drafting system, conventional manual "piecing-up" or mechanical reinstitution of yarn production as described by the aforementioned prior patents cannot be successfully attempted until the feeding of the roving strand is reinstituted. Practical experience with manual re-establishment of roving strand feeding has now revealed that certain unexpected difficulties are created by the effect of roving feed stop devices on the heretofore conventional construction of textile yarn spinning machine drafting systems.

More particularly, it is conventional for a textile yarn spinning machine drafting system to include a rear guide referred to as a "trumpet" through which a roving strand passes to reach a corresponding drafting system. In manually reinstituting drafting of a roving strand which has been interrupted at a point spaced rearwardly from the trumpet, it is necessary for an operator to thread the roving strand through the guide or

trumpet, in an operation similar to threading the eye of a needle. Such an operation, particularly where the trumpet is shielded from view, it is difficult and time consuming, unduly lengthening the time required to reinstitute production of yarn.

Having in mind the aforementioned difficulty, it is an object of the present invention to facilitate a reduction in the time required for an operator to reinstitute production of an attenuated strand by a drafting system for which roving strand feeding has been interrupted. In accomplishing this object of the present invention, a textile yarn spinning machine which cooperates with means for monitoring the delivery of attenuated strands and for interrupting feeding of roving strands is provided with a plurality of slotted trumpet means. The trumpets are arranged in a series adjacent the series of drafting systems with each of the trumpets being interposed between a corresponding drafting system and the point of interruption of roving strand feeding. By the provision of an outwardly opening slot passageway in each trumpet, roving strands may be introduced into the trumpet by lateral movement of an intermediate portion of a running length thereof, as distinct from the longitudinal threading motion otherwise required.

Some of the objects of the invention having been stated, other objects will appear as the description proceeds, when taken in connection with the accompanying drawings, in which

FIG. 1 is a perspective view of a textile yarn spinning machine in accordance with this invention;

FIG. 2 is an elevation view, partially in section and partially schematic, of the apparatus of FIG. 1;

FIG. 3 is an enlarged elevation view, taken generally along the line 3-3 of FIG. 2; and

FIG. 4 is an enlarged elevation view, partially in section, showing a portion of the apparatus of FIG. 2.

The accompanying drawings and the description which follows set forth this invention in the best mode contemplated by the inventor at the time that the drawings and description were prepared. However, it is contemplated that persons generally familiar with the art of textile manufacture will be able to apply the novel characteristics of the structure illustrated and described in other contexts by modification of certain details. Accordingly, the drawing and description are not to be taken as restrictive on the scope of this invention, but are to be understood as a broad and general teaching.

Referring now more particularly to FIGS. 1 and 2, a portion of the textile yarn spinning machine is there illustrated which includes a plurality of drafting systems respectively generally indicated at 10a, 10b, 10c and 10d. Each of the drafting systems comprises three cooperating sets of rolls including a set of rear rolls generally indicated at 11a (FIG. 2); front or delivery rolls 12a and intermediate rolls 14a. As is generally known to persons familiar with textile yarn spinning machines of the type illustrated, the series of rolls 11a, 12a, 14a define a series of aligned nips through which textile fiber generally indicated at F passes for attenuation.

Adjacent the delivery rolls 12a is disposed a vacuum end collection nozzle 16 into which attenuated fiber is delivered in the absence of production of an attenuated strand or yarn Y. Delivery of fiber F into the drafting system is accomplished by the delivery thereof of a roving strand R.

Cooperating with the plurality of drafting systems 10a, 10b, 10c and 10d which are arranged in a series is means for monitoring delivery of the attenuated strands Y and for responding to breakage of an attenuated strand by interrupting the feeding of the corresponding roving strand R at a point in advance of introduction thereof into the corresponding drafting system. In the form illustrated, this means generally is an embodiment of the invention disclosed and claimed in related U.S. Pat. No. 3,726,072 issued Apr. 3, 1973 to Ford et al. To the extent that the illustrations and descriptions set forth in that prior patent are necessary for a clear understanding of the present invention, they are hereby incorporated by reference into this description. It will be noted that illustrations which accompany this description include showings of roving feed stop members generally indicated at 20a, 20b, 20c, 20d which are mounted adjacent corresponding drafting systems for independent pivoting movement between a first position withdrawn from the corresponding roving strand R (as illustrated in FIG. 1 and in the full line position in FIG. 2) and a second position intersecting the roving strand (as shown in the phantom line position of FIG. 2). When a roving feed stop member 20a is moved to the second position (in accordance with the operation described in aforementioned U.S. Pat. No. 3,726,072) the feeding of the corresponding roving strand R into the drafting system is interrupted and the roving strand typically parts intermediate the roving feed stop device and the drafting system.

In accordance with this invention, the textile yarn spinning machine is provided with a plurality of slotted trumpet means arranged in a series adjacent the series of drafting systems. One such slotted trumpet means, generally indicated at 21a, is visible in FIGS. 2-4. Each of the trumpet means is interposed between a corresponding drafting system and the point of interruption of roving strand feeding thereto. Preferably, a plurality of adjacent trumpet means are mounted upon a common support bar 22, as by threaded fasteners such as 35 a bolt 23 or the like which penetrates the trumpet means 21a and is threadingly received by the bar 22.

The slotted trumpet means 21a has a central opening 24 for normally guiding a corresponding roving strand into the corresponding drafting system. Preferably, the face of the trumpet means 21a which is directed toward the source of the roving strand R has the converging surfaces characteristic of the interior of the bell portion of a trumpet, from which the trumpet means 21a derives such identification.

In order to facilitate reducing the time required for an operator to reinstitute production of an attenuated strand by the corresponding drafting system, after roving strand feed has been interrupted, the trumpet means 21a has an outwardly opening slot passageway 25 extending from the central opening 24 for receiving a roving strand into the central opening by lateral movement of an intermediate portion of a running length of the roving strand (as indicated in FIG. 3). Preferably, the outwardly opening slot passageway diverges radially outwardly from the central opening (FIG. 3) to aid an operator in introducing the roving strand R into the central opening 24. Further, it is preferred that the lower portion of the outwardly opening slot passageway 25 be generally aligned with the upper surface of the bar 22, in order that an operator may engage the roving strand R with the bar 22 and slide the

strand sideways of the bar and into the central opening of the slotted trumpet means.

In operation, an operator who desires to reinstitute production of textile yarn at a drafting system where 5 a roving strand feed has been interrupted will return the corresponding roving feed stop device to the first position, by tipping the device upright. Then, the entrapped roving strand will be withdrawn from the device and grasped with two spaced apart hands of the operator 10 (FIG. 1). The operator may then move the intermediate portion of the running length of roving strand which is between the operator's two hands into engagement with the bar 22, sideways along the bar 22 into the trumpet, and between the rear rolls 11a. The operator 15 then may release the roving strand and the roving strand will be carried by the operation of the drafting system through the remaining rolls and delivered by the front rolls 12a. Reinstitution of the production of yarn Y then proceeds either by manual "piecing-up" or by 20 mechanical operation as referred to hereinabove.

In the drawings and specification, there has been set forth a preferred embodiment of the invention, and although specific terms are employed, they are used in a generic and descriptive sense only and not for purposes 25 of limitation.

That which is claimed is:

1. In the combination of a textile yarn spinning machine having a plurality of drafting systems arranged in a series for normally receiving a corresponding series of roving strands and delivering a corresponding series of attenuated strands, and means for monitoring delivery of attenuated strands and for responding to breakage of an attenuated strand by interrupting feeding of the corresponding roving strand at a point in advance of introduction thereof into the corresponding drafting system, an improvement which facilitates reducing the time required for an operator to reinstitute production of an attenuated strand by a drafting system for which roving strand feeding has been interrupted, the improvement comprising a plurality of slotted trumpet means arranged in a series adjacent the series of drafting systems, each of said trumpet means being interposed between a corresponding drafting system and the point of interruption of roving strand feeding thereto and having a central opening for normally guiding a corresponding roving strand into the corresponding drafting system, and an outwardly opening slot passageway extending from said central opening for receiving a roving strand into said central opening by lateral movement of an intermediate portion of a running length of the roving strand.
2. Apparatus according to claim 1 further comprising mounting bar means extending adjacent a plurality of the drafting systems for supporting the plurality of said trumpet means corresponding thereto and further wherein said outwardly opening slot passageway of each of said trumpet means is directed toward said mounting bar means.
3. Apparatus according to claim 1 wherein said outwardly opening slot passageway of each of said trumpet means diverges radially outwardly from said central opening thereof.

4. In the combination of means for monitoring delivery of attenuated strands and for responding to breakage of an attenuated strand by interrupting feeding of the corresponding roving strand at a point in advance of introduction thereof in the corresponding drafting system, an improvement which facilitates reducing the time required for an operator to reinstitute production of an attenuated strand by a drafting system for which roving strand feeding has been interrupted, the improvement comprising a plurality of slotted guide means arranged in a series adjacent the series of drafting systems, each of said guide means being of a predetermined dimension longitudinally of a roving strand passing therethrough and being interposed between a corresponding drafting system and the point of interruption

5
